UNITED STATES PATENT OFFICE

HENRY ROSE, OF CHICAGO, ILLINOIS

DESIGN FOR A DRINKING GLASS

Application filed February 23, 1932. Serial No. 42,970. Term of patent 3½ years.

To all whom it may concern:

Be it known that I, HENRY ROSE, a citizen of the United States, residing in Chicago, Cook County, Illinois, have invented a new, original, and ornamental Design for a Drinking Glass, of which the following is a specification, reference being had to the accompanying drawing, forming a part thereof,

The figure is a side elevation of a drinking glass, showing my new design, the glass being of circular contour in cross section.

I claim:

The ornamental design for a drinking glass substantially as shown and described.

HENRY ROSE.
